UNITED STATES PATENT OFFICE

110,170

DESIGN FOR A TEAPOT

Leonard Brindley, East Liverpool, Ohio, assignor
to The Hall China Company, East Liverpool,
Ohio, a corporation of Ohio

Application February 24, 1938, Serial No. 75,393

Term of patent 7 years

To all whom it may concern:

Be it known that I, Leonard Brindley, a citizen of the United States of America, residing at East Liverpool, in the county of Columbiana and State of Ohio, have invented a new, original, and ornamental Design for a Teapot, of which the following is a specification, reference being had to the accompanying drawing, forming part thereof,

I claim:—

The ornamental design for a teapot, as shown.

LEONARD BRINDLEY.
